FLUORESCENT LIGHTING FIXTURE

Kurt Versen, Tenafly, N. J.

Application December 9, 1947, Serial No. 143,044

Term of patent 14 years

(Cl. D48—23)

To all whom it may concern:

Be it known that I, Kurt Versen, a citizen of the United States, residing at Tenafly, in the county of Bergen and State of New Jersey, have invented a new, original, and ornamental Design for a Fluorescent Lighting Fixture, of which the following is a specification, reference being had to the accompanying drawing, forming part thereof.

In the drawing:

Fig. 1 is a side elevational view of a fluorescent lighting fixture showing my new design,

Fig. 2 is a top plan view thereof,

Fig. 3 is an end elevational view, and

Fig. 4 is a fragmentary bottom perspective view.

The dominant characteristics of my design

reside in the portions shown by means of full lines in the drawing.

I claim:

The ornamental design for a fluorescent lighting fixture, substantially as shown and described.

KURT VERSEN.
